UNITED STATES PATENT OFFICE.

RALPH J. REEDER, OF MOLINE, ILLINOIS.

CLAMP.

1,319,900.

Specification of Letters Patent.

Patented Oct. 28, 1919.

Application filed February 24, 1919. Serial No. 278,958.

To all whom it may concern:

Be it known that I, RALPH J. REEDER, a citizen of the United States, residing at Moline, in the county of Rock Island and 5 State of Illinois, have invented a new and useful Clamp, of which the following is a specification.

This invention relates to improvements in tools, and more particularly to an improved 10 clamp, the object of the invention being to provide a clamp so constructed that two pieces to be operated upon may be maintained in angular relation to each other.

A further object of the invention is to provide 15 an improved locking device whereby a pair of clamps may be adjustably secured at an angle to each other for the purpose of changing the angular relation of the pieces held by such clamps.

20 With these and other objects in view, the invention consists in the novel construction and combination of parts hereinafter more fully set forth.

In the drawings accompanying and forming 25 part of this specification,

Figure 1 is a side view showing a pair of clamps secured in angular relation to each other by means of my improved locking device;

30 Fig. 2 is a sectional view taken on the line 2-2 of Fig. 1; and

Fig. 3 is a similar view taken on the line 3-3 of Fig. 1.

The same characters of reference designate 35 the same parts in the different figures of the drawings.

In the embodiment of my invention herein illustrated, 2 is a clamp of the usual construction, formed of an I-beam 3 having a 40 curved end 4 having the usual clamping head at its extreme end, the opposite clamping head being swiveled on the end of a clamping screw 5 threaded in the upper end of a standard 6, which is provided at its 45 lower end with jaws adapted to engage the upper horizontal portion of the beam, the standard being slidable along said beam and adapted to be held in adjusted position by means of a web 7 carried thereby and provided with a node 8 which drops into one of the depressions or recesses 9 formed in the upper horizontal portion of the beam. This construction is well known. This clamp 2 will be referred to throughout the specification and claims as the main clamp.

A second clamp is provided, usually smaller than the clamp 2, but of similar construction, except that in the embodiment shown the beam portion is not I-shaped, and therefore the standard 11 is of stirrup form 60 at its lower end for engaging the under surface of the beam. I do not, however, regard this feature as material.

For adjustably securing the clamps 2 and 10 in angular relation to each other, I provide a locking device, which consists of a shoe 12 adapted to slide on the horizontal portion of the I-beam 3 of the main clamp and having jaws at its underside for engaging the inner surface of said horizontal portion. The top portion of the shoe is provided with an opening for the passage of a rivet 13. Mounted on said shoe is a U-shaped member 14, having an opening therein in which is seated a stirrup 15, the member 14 serving to steady the stirrup and give additional support thereto. The rivet 13 passes through the lower side of the stirrup 15 and is turned over upon itself, thereby securing the shoe 12 and the stirrup 15 together. The upper side of the stirrup 15 is provided with a threaded opening adapted to receive a setscrew 16, the lower end of which bears upon the upper face of the beam 19 of the second or smaller clamp. This 85 beam 19 is so formed as to fit the stirrup when placed therein either on its side or bottom face, the beam being provided at each side thereof with a concave recess 17 extending longitudinally thereof for the purpose 90 of reducing its weight and also serving as a seat for the end of the setscrew 16.

From the foregoing it will be seen that when it is desired to use the pair of clamps located angularly to each other the shoe 12 95 of the locking device is slid on the beam 3 of the main clamp to the desired point. The beam 19 of the other clamp is then slid through the stirrup 15 until the clamp is brought to the proper angular relation to 100 the main clamp. The setscrew 16 is then rotated so as to force the beam 19 down against the member 14. The stirrup is thereby drawn upwardly and its lower side engages the under surface of the beam 19, so that said beam is firmly clamped between the setscrew 16 and the lower side of the stirrup. At the same time, owing to the rivet connection between the stirrup and the shoe 12, the shoe is drawn upwardly so that 110

its jaws are forced into contact with the inner surface of the horizontal portion of the beam 3 of the main clamp. It will thus be seen that I have provided a locking device whereby on the turning of a single setscrew both clamps are firmly locked in any desired angular relation to each other. When it is desired to still further change the angular relation of the clamps, the beam 10 19 may be removed from the stirrup 15 and replaced therein on either of its sides, whereby the angular relation of the clamps may be very widely varied.

It is to be understood that by the use of 15 the terms "main" and "smaller" clamp it is not my intention to in any way limit my invention, but these terms are used merely as a convenient means of referring to the clamps, nor do I desire to limit my invention to the identical construction herein shown, since the device is capable of considerable mechanical change without departing from the spirit and scope of the invention.

25 Having thus described my invention, what I claim is:

1. The combination with a pair of clamps having beam portions, of a locking device including a pair of members one adapted to 30 engage the beam portion of each clamp and

slidable thereon, and means for locking said slidable members on said beam portions.

2. The combination with a clamp provided with a beam having a curved portion, 35 of a locking device adapted to slide on said curved portion and provided with means for carrying a second clamp, and means carried by said locking device for securing said clamps in angular relation to each other.

3. The combination of a clamp having a beam portion, a second clamp also having a beam portion, a locking device adapted to engage said beam portions and maintain 40 said clamps in angular relation to each other, and comprising a slidable shoe adapted to 45 engage the beam portion of the first clamp, a stirrup adapted to slide on the beam portion of the second clamp, said stirrup and shoe being secured together, and a setscrew threaded in said stirrup and adapted to bear 50 against the beam portion of the second clamp whereby said stirrup and shoe may be locked on the respective beam portions.

In testimony that I claim the foregoing as my own, I have hereto affixed my signature in the presence of two witnesses.

RALPH J. REEDER.
